United States Patent Office.

CHARLES C. SAVERY, OF PHILADELPHIA, PENNSYLVANIA.

Letters Patent No. 81,827, dated September 1, 1868.

IMPROVED WATER-COOLER AND REFRIGERATOR.

The Schedule referred to in these Letters Patent and making part of the same.

TO ALL WHOM IT MAY CONCERN:

Be it known that I, CHARLES C. SAVERY, of the city of Philadelphia, in the county of Philadelphia, in the State of Pennsylvania, have invented a new and useful Improvement in Water-Coolers and Refrigerators; and I do hereby declare that the following is a full and exact description thereof, reference being to the accompanying drawings making a part of this specification, in which—

Figure 1 is a side sectional elevation of my cooler and refrigerator.

Figure 2, a plan sectional view of the same.

Figure 3, a sectional view of the device by means of which I secure the spout to the metal of the water-tank, (enlarged scale.)

The nature of my invention consists in a peculiar mode of constructing water-coolers and refrigerators, in which are combined cheapness and strength, as will be hereinafter shown.

To enable others skilled in the art to make and use my invention, I will now proceed and describe its construction and operation.

A A is the wooden box or casing of my cooler.

N N is a non-conductor substance between the casing A A and the metallic sides, top, and bottom of the cooler.

C C C' P, figs. 1, 2, is the "ice-and-water tank," and C'' P C' C'' the air-chamber.

S' is a perforated shelf in air-chamber. As many as may be desired may be placed there in any suitable position.

S is the spout for the water-tank. It can be set on any face of the water-tank.

D is the door of air-chamber. It can also be placed either at the end or on any of the sides of the air-chamber.

h h h are holes, covered inside with a gauge, metallic or otherwise, to allow the vitiated air to pass out, and also keep insects out.

L is the top lid of the water-tank.

Both door D and lid L are made of wood and metal combined, and packed inside with the non-conductor substance N.

The above construction shows the general shape of construction my cooler is to have, viz, the space divided in but two compartments, one "air-chamber" in contact with one "ice-and-water tank."

When my cooler is to be made of sheet metal entirely, the simplest mode of construction seems to be bending one sheet, of proper size, so as to form the sides of both the "ice-and-water tank" and the "air-chamber" of one single-sheet of metal, one end, or one side, being left open to receive door D, and dividing the space into the two said compartments by means of a partition, P, soldered or riveted, or both, as shown in fig. 2.

But if I prefer making my cooler of cast metal, or cast and sheet metal combined, the simplest method is to build both compartments separately, and then to join them together by means of flanges and rivets, or solder, or both, in any of the known and usual ways.

I would here remark, that if this last mode of construction is preferred, the cooler still has the desired form, viz, but two compartments, one "ice-and-water tank," and one "air-chamber," the one side of the "ice-tank" forming the back or one side of the "air-chamber," no more riveting or soldering being needed in one than the other case.

I also will enamel my cooler in the following way:

When my apparatus is, as aforesaid, made entirely of sheet metal, I will apply to all its parts, viz, the inside or the outside, or the inside and the outside of all its metallic face, a coat of enamel of any color; but when I construct my cooler of cast metal, or cast and sheet metal combined, viz, when the two compartments are made separate, they should also be enamelled separately, and then jointed together, as afore described, or in any other suitable way.

This mode of enamelling my water-cooler throughout all its parts offers many important advantages:

First, it prevents the metal from rusting.

Second, it covers and closes all the pores of the metal.

Third, enamel being, like glass, a bad conductor, diminishes much the conductibility of the metal of the cooler or refrigerator, thereby retarding the melting of the ice, and in a measure preventing the entrance of heated or hot air in the "air-chamber."

Therefore, having described my invention, what I claim as such, and desire to secure by Letters Patent of the United States, is—

The combination and arrangement of the enamelled ice-and-water tank C C C P and its lid, L, with the enamelled air-chamber C' C" and its door D, constructed substantially as herein specified.

CHARLES C. SAVERY.
